CLAIM

We claim the ornamental design for a pump component, as shown and described.

DESCRIPTION

FIG. 1 is a top perspective view of a pump component in accordance with an embodiment of our new design; FIG. 2 is a bottom perspective view of the pump component of FIG. 1; FIG. 3 is a front elevation view of the pump component of FIGS. 1-2; FIG. 4 is a rear elevation view of the pump component of FIGS. 1-3; FIG. 5 is a left-side elevation view of the pump component of FIGS. 1-4; FIG. 6 is a left-side elevation view of the pump component of FIGS. 1-5; FIG. 7 is a top plan view of the pump component of FIGS. 1-6; and, FIG. 8 is a bottom plan view of the pump component of FIGS. 1-7.

The portions shown in broken lines in the figures depict unclaimed environmental subject matter, are for illustrative purposes only, and form no part of the claimed design. Similarly and where applicable, unshaded portions that appear between broken lines or beyond boundary or break lines in the figures form no part of the claimed design and indicate that a specific width, height and/or length forms no part of the claimed design.
